Primary Examiner — Shawn T Gingrich(74) *Attorney, Agent, or Firm* — Boardman & Clark LLP(57) **CLAIM**

The ornamental design for a connector barrel of a battery module, as shown and described herein.

DESCRIPTION

FIG. 1 is a front overhead perspective view of a connector barrel showing our new design;

FIG. 2 is a front underside perspective view thereof;

FIG. 3 is a back overhead perspective view thereof;

FIG. 4 is a back underside perspective view thereof;

FIG. 5 is a top plan view thereof;

FIG. 6 is a bottom plan view thereof;

FIG. 7 is a right side elevation view thereof;

FIG. 8 is a left side elevation view thereof;

FIG. 9 is a front elevation view thereof; and,

FIG. 10 is a back elevation view thereof.

The broken line portion of the figure drawings is included to show portions of the battery module connector barrel that form no part of the claimed design.

UNITED STATES PATENT AND TRADEMARK OFFICE
CERTIFICATE OF CORRECTION

PATENT NO. : D951,866 S
APPLICATION NO. : 29/771667
DATED : May 17, 2022
INVENTOR(S) : Nicholas E. Elison et al.

Page 1 of 1

It is certified that error appears in the above-identified patent and that said Letters Patent is hereby corrected as shown below:

On the Title Page

1. In Column 1, below "Related U.S. Application Data", delete Item "(60)" and insert Item -- (62) --, therefor.
2. In Item (60), under "Related U.S. Application Data", in Column 1, Line 4, delete "10,249,916." and insert -- 10,249,916 which is a provisional of application No. 62/146,853, filed on Apr. 13, 2015. --, therefor.

Signed and Sealed this
Thirtieth Day of April, 2024

Katherine Kelly Vidal
